BELT TENSIONING DEVICE

Donald E. Williamson, West Concord, Mass., assignor, by mesne assignments, to Kalvar Corporation, New Orleans, La., a corporation of Louisiana

Application May 11, 1955, Serial No. 507,634

1 Claim. (Cl. 95—77.5)

It is desirable for various purposes to utilize a nip between a drum-like structure and belt means fastened thereto and alternately winding on and unwinding from the drum, as the latter is reciprocated. In order to maintain firm contact between the drum and the belt at the nip, the belt must be tightly pulled around the drum periphery, regardless of the position of the drum. This situation is for example encountered in apparatus for photographic contact printing where two sheets—an original to be reproduced and the photographic stock—have to be brought into close contact in a nip of the above mentioned type which permits easy charge and discharge of the sheets and confinement thereof for exposure during a predetermined period of time.

Some of the objects of the invention are to provide a device for tightening a belt means around a rotating drum means to which one end of the belt means is fastened; to provide such a device which permits oscillatory movement of the drum and belt while maintaining the belt tension; to provide such a device which receives at a convenient location that part of the belt which is at any time not wound on the drum; to provide such a device which does not obstruct access to the nip defined by the drum and the belt; to provide a photographic exposure device for feeding a set of original and light sensitive sheets into a nip between a drum and a web for retaining it therein during a predetermined period of time and for removing it therefrom by a reverse movement; and to provide such a device which is suited for the mounting of an elongate light source within the drum. While the device according to the invention is especially suited for photographic purposes, it is useful wherever similar problems are present.

A summary indicating the nature and substance of the invention is as follows.

According to the invention, a device for tensioning a belt means wound on and fastened at one end to a rotatable drum means comprises a belt receiving roller rotatably mounted parallel to the drum means and having fastened thereto the other end of the belt means; a compensation roller rotatably mounted coaxially with the receiving roller; resilient means interposed between the two rollers for exerting an essentially constant torque; and rope or cable-like means wound about the drum means and the compensation roller in a sense opposite to that in which the belt means is wound thereon; whereby the resilient means maintains through the rope means a constant tension on the belt means, the tensions on the rope means and on the belt means opposing each other for all positions of the drum.

In a particularly practical aspect of the invention, the resilient means is a helical spring arranged about a pivot that coaxially connects the two rollers, and one end of which spring is fastened to the receiving roller whereas its other end is fastened to the compensation roller.

The following description of a typical embodiment illustrates these and other objects, and aspects of the

nature of the invention. This description refers to a drawing in which:

Fig. 1 is an axonometric view of a device according to the invention;

Fig. 2 is a schematic side elevation taken from the right-hand side of Fig. 1; and

Fig. 3 is an axial section through the end portion of the web receiving roller and the compensation roller, this part being indicated at T of Fig. 1.

Figs. 1 and 2 indicate at 11 an essentially linear source of light such as a high intensity gas discharge lamp of known design, supplied from terminals on either side of the tubular lamp envelope, one of which terminals is indicated at 11.1. The structural details of the lamp are not shown because they are not essential with respect to the present invention. The lamp 11 is surrounded by a translucent cylindrical drum 12 made of suitably strong material, such as Lucite. The drum is rotatably mounted on a frame by suitable means such as flange and supporting rolls on each side, as indicated at 14 and 15 of Fig. 2. The construction of these pivots is unessential with regard to the invention and therefore not described in detail.

Mounted rotatably on an axis *a* by conventional means is arranged a belt receiving roller 21 with pivot shaft 21.1 and, coaxial therewith, a spring barrel 22 which constitutes the compensation roller and is associated with the belt receiving roller 21 as shown at T in Fig. 3. The barrel 22 rotates on a shaft 25 which has a portion 25.1 of reduced diameter which portion is fastened in a bore 21.2 of the roller 21. A spring 31 is inserted in the annular space 32 of barrel 22, and one end 31.1 of the spring is fastened to the barrel 22 whereas the other end 31.2 of the spring is fastened to the face of roll 21. In this manner the roller 21 and the barrel 22 can rotate relatively to each other on 25.5 and 25.6 while both rolls rotate also on 21.1 and 25, respectively. Suitable lubrication being provided, the two rollers can rotate relatively to each other.

A belt means, such as a web 41 is fastened to a groove of the drum 12 for example by means of a strip 42 and screws 43. The web is wound around drum 12 for example to the extent indicated in Fig. 2, and wound in opposite direction around the receiving roller 21. In this position the larger portion is on the drum. When the web is unwound from the drum, it is received on the roller 21 which will then carry several turns of the web. The web is suitably fastened to the roller 21, for example in the manner in which it is fastened to the drum 12.

A cable or rope 71 is wound around the drum 12 in a direction opposite to that of web 41. The cable can be contained in an annular recess of the drum, which is not shown for the sake of simplicity. The cable 71 is also wound around the barrel 22 in opposite direction to the web 41 and it is suitably fastened to the drum and the roller as indicated at 41.1 and 41.2 of Figs. 1 and 2. The barrel 22 can be provided with a flange 22.1 in order to retain the rope in proper position. The free side of the roller 21 has suitable pivot means as indicated at 21.1 of Fig. 1, and bearings (not shown) are provided at 21.1 and 25. The device can be driven in various ways; the present embodiment is driven by way of a coupling indicated at 25.2. Reciprocating movement is provided by means of a suitable reversible drive connected to clutch 25.2.

The above described embodiment is intended for purposes of making photographic copies, where an original and a sheet of photographic paper are fed, with the assistance of the platform provided by the web, into the nip between drum and web, with the latter in the position

indicated in Fig. 2 by the position 42.1 of the web fastening strip 42, and the platform indicated at 41. The drum and the roller are then rotated into the position shown in Figs. 1 and 2 by strip 42, as indicated by arrow *b*, and are now ready for exposure by lamp 11. After exposure, the drum and the roller are rotated in the direction of arrow *c*, by reversing the drive which is coupled to the device at 25.2. It will be noted that, with the drum end of the web in position 42.1, practically the entire web has been received on roller 21.

In order to keep the original and the photographic paper in close contact when they are confined, for exposure to lamp 11, in the nip between the drum and the web, the latter must be drawn tightly around the drum, with constant tension; this tension is securely provided by the device T as follows:

The torsional tension of the spring 31 is so adjusted that it exerts a force between the cable 71 which is wrapped around the drum and the receiving roll in the opposite direction from that of the web 41. It will be evident that the web 41 will always be tightly wound in all positions of the cylinder, if an initial rotary tension is applied to the spring 31, for example upon fastening the rope at 41.2 to the receiving roller.

It should be understood that the present disclosure is for the purpose of illustration only and that this invention includes all modification and equivalents which fall within the scope of the appended claim.

I claim:

A device for the contact printing of photographic sheet material, comprising: a translucent drum rotatably mounted on a fixed essentially horizontal axis; elongate lamp means within said drum; a belt wound on and fastened at one end to said drum; a belt receiving roller rotatably mounted parallel to said drum on a fixed axis, with its surface appreciably separated from the surface of the drum, and having fastened thereto the other end of said belt which is wound thereon in a sense opposite to that on said drum so that the nip formed by said

drum and said belt presents an open end towards the receiving roller such as to form a platform in substantially fixed position provided by the belt portion between the two surfaces; a compensation roller rotatably mounted coaxially with and adjacent to said receiving roller; a cable wound about said drum and said compensation roller in a sense opposite to that in which said belt is wound on said drum and said receiving roller; torque means interposed between said rollers for tending to rotate said rollers in opposite direction; and means for reciprocating said drum and said rollers with said belt and said cable; whereby the torque means maintains through the cable a constant tension on the web for all positions of the drum, so that the photographic sheet material can be fed on the platform to the open end of the nip when the web is unwound from the drum, then brought into the nip for exposure by the lamp, by rotation of the drum and the rollers, and returned through said open end by reverse rotation, and wherein said compensation roller has an annular recess facing said receiving roller; one of said rollers has an axial bore and the other roller has an axial projection fitting said bore; and the torque means includes a spring means helically wound within said recess with one end fixed to one roller and with the other end fixed to the other roller.
